ATTORNEY

UNITED STATES PATENT OFFICE.

CEYLON STURDEVANT, OF CASTLE ROCK, COLORADO, ASSIGNOR TO GEORGE ROBINSON,
OF LARKSPUR, COLORADO.

CHAIN FASTENER.

Application filed July 25, 1921. Serial No. 487,318.

To all whom it may concern:

Be it known that I, CEYLON STURDEVANT, a citizen of the United States, residing at Castle Rock, in the county of Douglas and State of Colorado, have invented new and useful Improvements in Chain Fasteners, of which the following is a specification.

My present invention has reference to a means for attaching the ends of a skid or 10 other chain.

My object is to produce a fastening means for this purpose which shall be of a simple construction, easily and quickly arranged to engage with the links of a chain, and when 15 so engaged cannot be accidentally removed from the chain.

The foregoing, and other objects which will appear as the nature of the invention is better understood, may be accomplished 20 by a construction, combination and operative association of parts, such as is disclosed by the drawings which accompany and which form part of this specification.

In the drawings:—

Figure 1 is a view illustrating the application 25 of the improvement.

Figure 2 is a perspective view of the improvement per se.

Figure 3 is an approximately central longitudinal sectional view through the improvement.

As disclosed by the drawings, my improvement contemplates the employment of a body member which is formed of two 35 similarly constructed plates 1—1 respectively. The plates, at one of the ends thereof have outwardly directed portions in the nature of ears 2, and the edges of the plates aligning with the inner edges of the ears are notched, as at 3. Between the ears 2 there 40 is pivoted, as at 4 a blade 5. The inner edge of the blade, opposite its pivot is straight, as at 6 and from the said straight portion the said inner edge of the blade is notched, as at 7. The blade is really in 45 the nature of a flat plate, providing no sharpened edges and when swung to closed position between the plates that constitute the body, the notch 7 of the blade is arranged in alignment with the notches 3 of

the said body plates. The body plates are held in spaced relation by a spring rod 8. The rod 8, at the end thereof opposite that arranged between the ears is formed with an eye 9, the said eye being preferably 55 thickened, and passing through the eye and through the body plates 1 is a pivot member 10. The pivot member has its ends passing through eyes 11 in a yoke 12, the ends of the pivot being flattened, as at 13 60 against the said eyes of the yoke. Passing transversely through the body plates 1, at approximately the center thereof is a pin 14. This pin is in contacting engagement with the spring rod 8, and bows the said rod so 65 that the outer or free end thereof, when in contacting engagement with the straight edge 6 of the blade effectively holds the blade in closed position. The notches of the body plates and the notch of the blade 70 provide for the reception of an end or other link 15 of a chain.

A construction, as above described, is extremely simple, and may be cheaply manufactured and marketed. The spring effectively holds the blades in closed position, and while the link may be readily received 75 between the blade and body, the same cannot be accidentally separated therefrom.

Having described the invention, I 80 claim:—

1. A chain fastener comprising a body formed of two spaced plates having outstanding ears at one end thereof and their edges notched at their said ears, a notched 85 blade pivoted between the ears, a spring rod having an eye end which is pivoted between the plates near the ends thereof opposite those provided with the ears, and an element passing transversely through the 90 plates engaging the spring rod for centrally bowing the same and for causing the free end of said rod to exert a pressure against the inner edge of the blade opposite the pivot therefor.

2. A chain fastener comprising two parallel body plates each having an outstanding ear at one end thereof and each being notched inward of its ear, a flat plate comprising a blade pivoted between the ears 100

and said plate having a notch to align with the body plates when the blade is closed therebetween, a spring rod having an eye end arranged between the body plates, a pivot passing through the eye, a yoke on the body plates engaged by said pivot and an element passing transversely through

the body plates engaging and bowing the spring between the eye and the free end thereof which contacts with the edge of the 10 blade opposite its pivot.

In testimony whereof I affix my signature.

CEYLON STURDEVANT.
